[57] CLAIM

The ornamental design for a three-dimensional puzzle, as shown and described.

DESCRIPTION

FIG. 1 is a front view of a three-dimensional puzzle. FIG. 2 is a rear elevational view thereof. FIG. 3 is a left side elevational view thereof, the right side elevational view being a mirror image of the left side view. FIG. 4 is a top plan view of the three-dimensional puzzle; and, FIG. 5 is a bottom plan view thereof.
